Primary Examiner—Sandra L. Morris*Attorney, Agent, or Firm*—Pearne, Gordon, McCoy & Granger[57] **CLAIM**

The ornamental design for a refrigerator door ice dispenser insert, as shown and described.

DESCRIPTION

FIG. 1 is a front elevational view of a refrigerator door ice dispenser insert, showing our new design, the broken line showing of the refrigerator is for illustrative purposes only, and forms no part of the claimed design;

FIG. 2 is a top perspective view thereof;

FIG. 3 is a perspective view of a second embodiment thereof, the only difference being the absence of the removable spill tray; and,

FIG. 4 is a bottom perspective view of FIG. 1.

The sides not disclosed are plain and unornamented.
